UNITED STATES PATENT OFFICE.

MAX HILDEBRAND, OF AUGSBURG, GERMANY.

CLOCKWORK.

Application filed April 12, 1922. Serial No. 551,998.

To all whom it may concern:

Be it known that I, MAX HILDEBRAND, a citizen of the German Republic, residing at Augsburg, Germany, have invented certain new and useful Improvements in Clock-works, of which the following is a specification.

This invention relates to a clockwork, all the parts of which, with the exception of the shafts and springs are made according to the process for casting molten metal under pressure and are of peculiar moulding on account of the manufacturing process.

For making the manufacturing of clocks more rational the tendency has prevailed hitherto to simplify the clockwork. This measure alone is however not sufficient to ensure the greatest economy in the manufacturing as the working of the individual parts and the putting together of the same is facilitated only in the measure determined by the reduction of the elements.

According to this invention an economy in the manufacturing of clocks is realized in a degree which has not been dreamed of, by applying the process of casting molten metal under pressure. The elements of the clock-work are produced in one simple operation in the final shape if the said process is used. Certain elements, which have hitherto been composed of different parts can now be made in one piece and by one single operation. For putting together a clockwork composed of these improved elements it is merely necessary to insert the sets of wheels and the speed regulator between the frame plates, to put the dial in place and to insert, if desired, the clockwork in a casing.

In order that the invention may be clearly understood, I shall proceed to describe the same with reference to the two forms of construction shown, by way of example, on the accompanying drawing, wherein:—

Figs. 1 and 2 show the first form of construction respectively in elevation and in section.

Fig. 2^a shows in detail the sprocket wheel 18 of Fig. 2.

Fig. 2^b shows in detail the wheel 11 of Fig. 4, and

Fig. 2^c shows in detail the trigger 12^b of Fig. 4.

Figs. 3 to 6 show as second form of construction an eight days clock work with a spring as winding up device.

Fig. 3 is a front elevation of the clock-

work, the spring barrel being partly shown in section.

Fig. 4 is a vertical section through the clockwork.

Fig. 5 shows the regulating device on enlarged scale in elevation.

Fig. 6 is a section on line A—B of Fig. 5.

Referring to Figs. 1 and 2 the sets of wheels of the clockwork are mounted in two frame plates 1 and 2 in which the bearings for the journals of the wheel shafts are produced by casting. Spacing pins 3, 4, 5, upon which the dial is to be fixed and spacing pins 6, 7, 8 terminating in journals and designed for the fixing of the frame plate 2 are cast on the frame plate 1. Upon the surface of frame plate 1 turned towards the dial a journal 9 for the change wheel and a calotte 10 are cast on further, said calotte being designed for the shaft of the minute wheel.

Owing to the provision of the calotte 10 the quarter-wheel 25 can be keyed upon that part of the shaft for the minute wheel which is enclosed between the two frame plates, said quarter wheel 25 meshing with the change wheel 27 mounted upon the journal 9 and serving to transmit the movement of the hour wheel.

In consequence of the form of construction of the frame plates which has been described, the shaft for the minute wheel with the sprocket wheel, and the minute wheel with the quarter wheel can be each made in one piece to be mounted, together with the additional wheel, the anchor wheel and the regulator, between the frame plates, the change wheel and the hour wheel with the hour tube being pushed finally upon the journal 9 and upon the shaft 19 of the minute wheel.

The only work to be done on the frame plates, besides the drilling of the holes for the split pins 26, consists in the cutting of a female thread in each frame plate for the screwing in of the center-points 11 and 12 between which the speed regulator is mounted. The speed regulator 13 is constructed like a beam mounted upon the anchor shaft and suspended to the spring 14 so that it can oscillate in a perpendicular plane. The speed of the clockwork is regulated by the spring 14. The tensioning screw of the spring 14 is guided in a hole of the spacing pin 6.

The movement of the clock consists of the anchor wheel 15 with pinion, the interme-

diary wheel 16 with pinion, and the minute wheel 17 with the sprocket wheel 18. The anchor wheel 15 with pinion, and the intermediary wheel with pinion are so constructed that the hubs of these wheels merge directly into the pinions and are cast together with the pinion on the shafts. The sprocket wheel 18 is constructed in the usual manner and has on its side turned towards the minute wheel a steel disk *a* with two elastic flaps *a'*, obtained by stamping, and which engage with axial teeth *b* of the minute wheel 17. The minute wheel and its sprocket wheel are loosely mounted upon the shaft 19 and pressed the one against the other or against the adjusting collar 21 of the shaft 19 by the action of spring 20 which is inserted between the minute wheel and the hub of the quarter wheel 25 keyed upon the shaft 19.

In this manner there is insured on the one hand a friction coupling between the minute wheel and its shaft which is necessary for the regulation of the clock, and on the other hand the proper working of the spring trigger mounted upon the sprocket wheel.

The sprocket wheel is constructed in the usual manner. It has upon its surface turned towards the minute wheel a steel disk *a* with two elastic flaps *a'* obtained by stamping which engage with an axial tootheing *b* of the minute wheel 17. This axial tootheing of the minute wheel is not made of squirmed cast as such material would not be suitable for this element. The tootheing is punched out of an iron disk which is cast into the minute wheel.

The minute hand is mounted directly upon the square of the shaft of the minute wheel. The movement of the hour hand is transmitted from the shaft of the minute wheel by the intermediary of the change wheel 27 and transferred to the hour wheel 23 which is cast in one piece with the hour tube 24 by squirmed casting.

Referring to Figs. 3 to 6 the sets of wheels of the clockwork are mounted between two frame plates 1, 2 in which the journal bearings for the wheel shafts are cast. Upon the front plate 1 the spring barrel 3, the spacing pins for fixing the dial and the pin for fixing the frame plate 2 are cast on. The frame plate 2 has, besides the journal bearings and the holes for the reception of the spacing pins, a slit 4 for the adjustment of the guide spring 22 of the speed regulator.

The spring barrel 3 is formed like a capsule closed at the front part and open at the back. In the journal bearing 5 which is cast on centrically the spring shaft 6 is guided, the square end 6^a of which serves for the winding up of the spring, projects at the front side of the clockwork.

65 The fact that the barrel is cast according

to the process of casting molten metal under pressure permits a fixation of the spring 7 which is not possible with the barrels commonly use. This fixation is effected by a recess 8 in the inner circumference of the barrel, the depth of which corresponds approximately to the strength of the intermediary spring 7^a and which serves to receive this spring. The spring 7^a engages with one end in the undercut edge 9 of the recess 8, its other end being embraced by the end of the main spring 7. The intermediary spring 7^a is thus held, so to say, in two articulations so that the end of the main spring has free play in radial direction. If the main spring is put completely under tension its end can be in close contact with the last spiral winding, whilst on the other hand at the unwinding of the spring the several layers of the spring can adapt themselves to the inner surface of the casing in the shape of a regular spiral.

The losses from friction between the individual windings of the winding up spring are reduced to the minimum by this accurate guiding. The cover plate 10 of the barrel acts in the same sense. This cover plate is loosely placed upon the stepped spring shaft 6 and the circumference of the cover plate engages with slight play in a circular groove 3^a of the spring barrel 3. If at the unwinding of the spring some of the windings should be pressed against the cover plate 10 this cover plate can participate in the revolving movement of the spring windings whereby the loss of power resulting from the sliding friction of the spring spirals upon the cover plate is avoided.

The spring 7 is fixed upon the spring shaft in the well known manner by the pin 6^b. In order to facilitate the putting together of the spring barrel the boring of the cover plate has an opening 10^a which corresponds in size with the spring pin 6^b, so that the spring shaft 6 can be inserted after the spring has been pushed on to the barrel and after the cover plate 10 has been put upon the barrel.

The spring wheel 11 driven by the spring is not rigidly connected with the shaft 6 but by means of the trigger 12^b which is constructed as usual. The teeth with which the trigger engages are however not cast into the toothed wheel 11 but stamped into an iron disk 12^a which is cast into the toothed wheel 11. The spring wheel 11 meshes with a pinion 13 cast in one piece with the minute wheel 14 and loosely mounted upon the shaft 15 of the minute wheel.

The coupling between the minute wheel 14 and its shaft 15 is effected in the well known manner by the spring 16 acting as coupling means, inserted between the minute wheel 14 and the hub of the quarter wheel 17. The minute wheel meshes in the well

known manner with the pinion of the auxiliary wheel 18 which in its turn meshes with the pinion of the anchor wheel 19.

The mutual displacement of the shafts of the auxiliary wheel and of the anchor wheel with regard to the vertical through the axis of the speed regulator is important on account of the mounting of the spring 21 for the speed regulator. The minute wheel 10 with its pinion, the auxiliary wheel with its pinion and the anchor wheel with its pinion are all cast in one piece by squirted casting and cast on their shafts.

The speed regulator is constructed like a beam and consists of the two-armed lever 20 with the fly weights 23; it is fixed, together with the anchor 24, upon the shaft 25. The two ends 26 of the shaft 25 are shaped like knife edges in such a manner that the knife edges coincide with the middle line of the shaft. The knife edges rest in two bearings 27 which are worked into the bearing plates 28 screwed upon the outer surfaces of the frame plates.

Care has to be taken that the edges along which the knife edges are in contact with the bearings be situated in the axis of the borings of the frame plates into which projects the shaft 25 of the speed regulator. The borings of the frame plates have a slightly greater diameter than the shaft of the speed regulator so that this shaft, supported exclusively by the knife edges can move without friction in the borings of the frame plates which serve merely to prevent the knife edges from jumping out of the bearings in case the clockwork should be shaken.

The axial play of the bearing of the speed regulator is limited by the cover plates 29 which cover the bearings 27 from the outside. In order to reduce as much as possible the friction which could occur eventually between the ends of the knife edges and the cover plates, the ends of the knife edges are bevelled towards the back so that they can come in contact with the hardened cover plates only with the point which is situated in the middle axis of the shaft.

An elastic steel wire 21 serves as spring for regulating the oscillations of the beam, said steel wire being inserted into a vertical boring 30 of the shaft of the speed regulator and fixed in the same by wedges. The other end of the steel wire is guided in a spring guide 22 whose distance from the shaft of the regulator is adjustable. This spring guide is formed by an angular sheet metal piece one arm of which is bent over parallel with the shaft of the regulator and provided with a slit 22^a in which the spring is guided, the other arm being in contact with the frame plate and riveted together with a bolt 31 adjustable in a vertical slit 4 of the plate of the frame. The bolt and

with it the angular sheet metal piece are pressed against the plate of the frame by the elastic plate 22^b which is fixed upon the bolt by the pin 32.

By vertical displacement of the spring 70 guide 22 the useful length of the steel wire 21 can be varied and the direction of each oscillation of the speed regulator and consequently the rate of the clock can thus be regulated. Another measure, connected 75 with the construction of the speed regulator, consists in that the shafts of the anchor wheel and of the intermediary wheel are mutually displaced with regard to the vertical middle line so far that they do not impede the play of spring 21.

I claim:—

1. In a clockwork in combination a frame plate, bearings for the journals of the wheel shafts, spacing pins for the fixing of the dial, spacing pins terminating in journals and designed for the fixing of a second frame plate, a journal for the shaft of the minute wheel, a bracket for the shaft of the centre wheel and the spring barrel all these parts being made in one piece according to the process of casting molten metal under pressure, an escape wheel and its pinion made in one piece according to the process of casting molten metal under pressure, a fourth wheel and its pinion made in one piece according to the process of casting molten metal under pressure, a centre wheel and its canon pinion made in one piece according to the process of casting molten metal under pressure, 90 a minute wheel and its pinion made in one piece according to the process of casting molten metal under pressure and an hour wheel with its hour tube made in one piece according to the process of casting molten metal under pressure, 95 100

2. In a clockwork in combination a frame plate, bearings for the journals of the wheel shafts, spacing pins for the fixing of the dial, spacing pins terminating in journals and designed for the fixing of a second frame plate, a journal for the shaft of the minute wheel, a bracket for the shaft of the centre wheel and the spring barrel all these parts being made in one piece according to the process of casting molten metal under pressure, an escape wheel and its pinion made in one piece according to the process of casting molten metal under pressure, a fourth wheel and its pinion made in one piece according to the process of casting molten metal under pressure, a centre wheel and its canon pinion made in one piece according to the process of casting molten metal under pressure, 110 115 a minute wheel and its pinion made in one piece according to the process of casting molten metal under pressure, a steel disk cast in the sprocket wheel of the minute wheel facing said 120 125 130

tre wheel and having an axial toothing obtained by stamping, an hour wheel with its hour tube made in one piece according to the process of casting molten metal under pressure, a chain wheel and a locking spring engaging with the axial toothing of said steel disk.

In testimony whereof I affix my signature in the presence of two witnesses.

MAX HILDEBRAND.
